IMPULSE-REPEATING ELECTROMAGNETIC RELAY

John I. Bellamy, Wheaton, Ill., assignor, by mesne assignments, to International Telephone and Telegraph Corporation, a corporation of Maryland

Application October 12, 1951, Serial No. 250,974

4 Claims. (Cl. 179—16)

1

This invention relates to an impulse-repeating electromagnetic relay, and its primary object is to provide a relay of that kind which will respond with improved faithfulness over a wide range of series and shunt resistance conditions of the signal line over which the impulses are received.

This application is a continuation in part of my prior application for Electromagnetic Relays, Serial Number 687,629, filed August 1, 1946.

GENERAL DESCRIPTION

A simple, reliable, and economical form of electromagnetic relay widely used in telephone switchboards and in related fields is based on a U-shaped magnet structure, made up of an L-shaped magnetic return plate and an electromagnet which lies parallel to the longer arm of the return plate, with one end secured to the shorter arm. An armature, mounted on the free end of the return plate and attractable to the electromagnet upon energization thereof, controls one or more sets of contact blades mounted on the return plate. Among other uses, such a relay is used as a line relay to repeat direct-current control impulses into local circuits.

Reference is made to "Telephony, Including Automatic Switching," by Smith; Frederick J. Drake and Co., 1924. Figure 203 of that publication shows a line relay LR of a selector switch and of a connector switch controlled successively by series of impulses received over a line from a calling telephone. Chapter XXIII, Testing and Adjustment of Automatic Apparatus, starting on page 371 of that publication, points out that the pulsing mechanism of the telephone calling device is adjusted to give a normal impulse "speed" (frequency) of about ten per second; that a ratio of about 65 percent break of the impulse contacts is common; and that, in one example, the extreme test limits of the line-resistance range over which a line relay can successfully repeat the impulses at a rate of fourteen per second (see paragraph starting on page 379) are, respectively, (1) a zero loop with a 20,000-ohm leak, and (2) a 1,200-ohm loop with no leak. In another example, the extremes are (1) a zero loop with a 15,000-ohm leak, and (2) a 750-ohm loop with no leak.

It is clear that the repeated impulses are greatly distorted under each of the extreme line conditions, comprising, (1) a line of minimum line resistance, but with poor insulation and consequent high line leakage, and (2) a line of maximum line resistance, but with good insulation and consequent low line leakage. As the noted

publication makes clear, a line relay adjusted to meet both extremes operates early and restores late under the first extreme condition, while it operates late and restores early under the second extreme condition. On analysis, this appears to be the necessary consequence of a relay of the noted character, wherein the armature is acted upon by an electromagnet which supplies a variable operating force in but a single direction, and is opposed by the fixed restoring-spring load of the contact-blade assembly.

For the first noted extreme condition (a line of minimum series resistance and maximum leakage), the armature of a relay having a correct basic adjustment (armature stroke and "residual" air gap) requires a heavy restoring force to insure that it restores with reasonable promptness when the line is opened at the impulse contacts. The magnetic structure of the relay is then at its highest point of magnetic saturation, and the high magnetic energy tends to dissipate slowly because of the shading effect of the low shunt resistance. Moreover, eddy currents and the residual tendencies present in the magnetic structure tend to cause the armature of a highly saturated relay of this type to restore late unless the restoring spring force is substantial.

When the same relay, so adjusted and with the noted necessarily heavy restoring-spring load, is used for the second noted extreme condition (a line of maximum series resistance and negligible leakage), the armature restores more quickly because the flux level of the magnetic structure is much lower. This action, coupled with the fact that the high series resistance causes the armature to operate much later on the closure of the impulse contacts, causes a very large change in the break-make ratio of the repeated impulses. In practice, the restoring-spring force is so regulated that the departure from the most desirable ratio is shared about equally between the two extremes of line conditions. Then the most desirable break-make ratio of the repeated pulses occurs when the connected line has a combination of series and shunt resistances falling about half way between the two extremes.

In order to relieve the noted distortion of repeated impulses, arising from using the same armature-restoring force for all line conditions, the relay of the present invention is arranged to apply an auxiliary magnetic restoring force to the armature, and to vary that force between minimum and maximum from instant to instant as required. For this purpose, the relay of the present invention is provided with an auxiliary pole

member in the form of a branch pole member having a shading device thereon. The branch pole member acts upon the armature in opposition to the normal tractive pole member, whereby the armature is operated by the main, unshaded pole member at the beginning of an impulse, and is restored by the action of the auxiliary, shaded pole member at the termination thereof. By this arrangement, (1) the range of line conditions over which the relay can repeat impulses of tolerable ratio is increased, and (2) the impulses repeated by the relay over the extreme range of known relays are of a comparatively uniform break-make ratio.

Other objects and features will appear as the description progresses.

The drawings

Referring now to the drawings, comprising Figs. 1 to 6,

Figs. 1 to 3 show respectively a side, top, and front view of relay R1, comprising the preferred embodiment;

Fig. 4 shows a partial side view of relay R2, comprising a desirable modification of relay R1 of Figs. 1 to 3;

Fig. 5 shows a typical circuit use of relay R1 (Figs. 1 to 3); and

Fig. 6 shows a modification of Fig. 5 which uses relay R2 (Fig. 4).

Preferred embodiment (Figs. 1 to 3)

Referring now to Figs. 1 to 3, relay R1, the preferred embodiment, includes an L-shaped magnetic return plate 2, having the core 6 of the electromagnet fixed thereto by screw 7. Spoolheads 7 and 9 are fixed with core 6 to define a space for windings 3, separated by washer 50. Four winding terminals 10 are fixed with spoolhead 9. The spoolheads 3 and 9 are preferably of a similar half-circular and half-square shape, as shown for the spoolhead 8 in Fig. 3. The circular half of spoolhead 9 is uppermost, while the square half of spoolhead 8 is uppermost, providing a sturdy surface which rigidly supports the front end of member 2 and holds the electromagnet against rotation.

Armature 5 is supported on pivot rod 18, which passes through ears 21 of the armature and ears 17 of bracket 15, secured to member 2 by screws 16. Bracket 15 is preferably of magnetic material to provide a comparatively large area of return air gap between armature 5 and part 15, and thence through member 2. Strip 19, of non-magnetic material, is secured to part 15, as by rivets 20, to act as a front stop for armature 5 in its forward motion toward the main, tractive pole member 4.

The contact mechanism of the relay is contained in assembly 30 of Figs. 1 and 2, including clamp plates 34 and 43, secured together by clamp screws 44, and retained on member 2 by screws 45.

The contact assembly includes two columns, 31 and 32, of contact blades. Each column includes a lower fixed contact blade 37, an intermediate, traveling contact blade 39, and an upper, fixed contact blade 41. The fixed contact blades 37 and 41 are preferably of substantially greater thickness than the traveling contact blade 39, the thickness of which is accentuated in the drawing to avoid crowding of the lines.

Actuation of the contact mechanism is accomplished by the T-shaped rear arm 22 of the armature 5, through the medium of the relatively

thin actuating blade 35 and the overlying insulating actuator 47.

The fixed contact blades 37 and 41 are each provided with windows 48 (Fig. 2), to permit actuator 47 to move freely therethrough. Each contact blade has a rear terminal portion 33 for the attachment of a conductor thereto. The contact blades are maintained insulated from each other and from the clamp plates 34 and 43 by insulating plates 36, 38, 40, and 42.

The normal position of armature 5 is determined by back-stop arm 23, which rests on the nonmagnetic plate 25, retained in position beneath the assembly 30.

Bending of actuating arm 22 of the armature to bring the movable contact elements to the desired position (with armature 5 fully operated and resting against stop member 19), as well as the bending of back-stop arm 23 to determine the normal position of armature 5, is facilitated by slots 24 through the arms 22 and 23 for receiving a suitable adjustment tool.

Movement of armature 5 responsive to energization and deenergization of the windings 3 is controlled jointly by the main, actuating pole member 4 and the auxiliary, restoring pole member 51. Member 51 is encircled by a conducting shading device 52, composed of a desired number of laminations of a conducting material such as copper.

Pole members 4 and 51 are secured to the front end of core 6 by screw 11, which passes through enlarged or vertically slotted openings in parts 4 and 51 to permit vertical adjustment of these parts before the final tightening of screw 11.

For most uses of the relay, the tractive face of pole member 4 is a substantial distance below the upper face of front stop member 19, to leave a substantial "residual" air gap between parts 4 and 5 with the armature 5 in its operated position, and part 51 is sufficiently high that about the same air gap normally exists between it and the upper surface of armature 5. It will be understood that armature 5 is maintained in that position in the illustrated embodiment by the relatively light spring load imposed by parts 39 and 35.

When a substantial current flow occurs in windings 3, pole members 4 and 51 are both magnetized and each attracts armature 5. Conducting shading member 52, however, delays the passage of flux through member 51, with the result that armature 5 is effectively attracted by member 4 and moves to operated position against the upper-face of stop-member 19 before the flux through pole member 51 can reach an effective restraining value. Incidental to this armature movement, actuating arm 22 raises actuating spring members 35 to thereby raise actuators 47. Contact blade 31 of each column (31, 32) is thereby lifted out of engagement with its fixed contact member 37, and is brought into effective engagement with its fixed contact member 41.

When the current flow through the windings 3 is subsequently terminated, pole members 4 and 51 are consequently demagnetized, but the demagnetization of pole member 51 is delayed by the shading action of member 52, with the result that armature 5 is thereby attracted to its illustrated restored position, in aid of the restoring force exerted by spring members 35 and 39.

Reversed-action embodiment (Fig. 4)

Referring now to Fig. 4, the relay R2 shown

therein is exactly similar to the relay R1 of Figs. 1 to 3 except that shading member 52 has been shifted from restoring pole member 51 to actuating pole member 4.

When the windings 3 of relay R2 are energized to magnetize pole members 4 and 51, member 51 becomes magnetized immediately, while the passage of flux through pole member 4 is delayed by the action of the conducting shading member 52. As a result, armature 5 remains in normal position.

When the current flow through the windings of relay R2 is discontinued, pole member 51 demagnetizes with comparative promptness, while shading member 52 delays the demagnetization of pole member 4 for an interval. During this interval, armature 5 is operated by member 4. If the windings remain currentless until the effect of shading member 52 has died away, armature 5 is then restored by spring action.

In the normal intended use of relay R2, hereinafter described, the establishment of current flow through the windings of the relay is followed by a series of impulses in the form of momentary current interruptions. As a consequence, the armature of the relay is attracted to pole member 4 upon the first interruption and remains so attracted until the current flow is resumed, whereupon it is magnetically restored by the overpowering action of pole member 51, remaining thus restored until the next interruption occurs.

Circuit use of relay R1 (Fig. 5)

Referring now to Fig. 5, a simplified typical contemplated use of the relay R1 of Figs. 1 to 3 will be described.

500 represents the control station, which may comprise a dial telephone, with 510 representing the normally open hookswitch contacts and 511 representing the impulse contacts of the dial calling device. Conductors 512 are the usual line conductors in a two-wire signalling system, such as the conductors of a dial telephone line. LS represents a partially illustrated line switch of the type indicated in Fig. 203 (opposite page 268) of the cited publication, the arrangement being such that any one of a number of lines such as 512 can be switched into connection with the relay R1. Each lineswitch LS may have access to a number of the digit recording circuits, and each such circuit may be accessible to a number of lineswitches LS. The symbols 517 indicate multiple connections to the contact banks of other lineswitches LS.

Relay R1 (of Figs. 1 to 3) cooperates with the associated hold relay 521 in controlling a stepping switch SS1. In a dial telephone system, the stepping switch is used to extend the conductors of a calling line to, or toward, the conductors of a called line, but for simplicity of disclosure the switch SS is illustrated as controlling the lighting of display lamps 550.

Stepping switch SS includes a brush 527 having the illustrated normal position and having ten off-normal positions in which it engages its associated contacts 1 to 10 respectively.

It is advanced by stepping magnet 523, and is returned to normal by the usual restoring spring (not shown) upon the operation of release magnet 526.

Station 500 may be at some distance from the apparatus controlled therefrom, or it may be a station comparatively close to the apparatus. The resistors 513 and 514 represent the distributed wire resistance of the line 512, and resistors 515 and 516 represent distributed leakage between the

wires of the line, such as may result from wet, broken, or missing insulators; contact between bare line wires and tree branches; or moisture in a cable.

5 Parts 8, 9, and 22 may each have a 1-inch width; core 6 may be three eighths inch in diameter; and the other parts may be generally in proportion according to the scale used in the drawing. With this proportioning, each of the windings 3 may comprise about 4000 turns of No. 34 enameled copper wire, having a resistance of approximately 200 ohms. With a battery of about 50 volts, such as is commonly used in the central exchange of a dial telephone system, the relay R1 has been found to repeat dial impulses satisfactorily, without change of adjustment, over lines 512 ranging from substantially zero to 1800 ohms series resistance, represented by resistors 513 and 514 on the drawing, and with leakage (shunt resistance) ranging between infinity and 3600 ohms, represented by resistors 515 and 516.

Operation of Fig. 5

When digit information is to be transmitted from station 500 of Fig. 5, hookswitch contacts 510 are first closed; impulse sending contacts 511 are then caused to open momentarily a number of times to deliver a series of "break" impulses over the line 512; and hookswitch contacts 510 are later opened when the transmitted registration is to be cleared out.

Upon the closing of hookswitch contacts 510, and if the lineswitch LS is controlled as is the one shown in Figure 203 of the cited publication, the usual operations of switch LS occur to extend the calling line 512 to an idle circuit such as the one illustrated. Thereupon, the two windings 3 of line relay R1 are energized in series over line 512, by current supplied from the ungrounded negative pole of a grounded current source (not shown) assumed to be of approximately 50 volts in accordance with the usual signalling and dial-telephone practice.

As the current rises in the windings 3 of relay R1, there is an in-phase rise of flux through pole member 4 of Fig. 1, and a much slower rise of flux through pole member 51 because of the retarding action of shading member 52. As a consequence, a greater tractive force is exerted on armature 5 by the pole member 4 than is then exerted by the shaded pole member 51. Armature 5 therefore moves promptly into engagement with its front-stop member 19, being then nearer to member 4 than to member 51. By the armature movement, contact blade 19 is moved away from member 37 and into engagement with member 41, as previously described. The engagement of parts 39 and 41 closes a circuit for hold relay 521, which relay thereupon operates. At its contact arm 528, it disconnects contact member 37 from the release wire 524 and connects it to the stepping wire 522, in preparation for transmission of impulses to stepping magnet 523.

On each momentary interruption of the line current incident to the noted operation of impulse-sending contacts 511 (as upon the restoration of the usual telephone calling dial), armature 5 of the relay R1 is promptly restored, the action being enhanced, as previously noted, by the prompt cessation of flux in pole member 4 as compared to the flux in pole member 51, which persists by virtue of the retarding action of shading member 52.

At the end of each momentary interruption impulse, the resumption of normal current flow

through the windings 3 of relay R1 causes armature 5 of the relay to reoperate as described for the initial closure of the line circuit.

On each restoration of relay R1, the circuit of hold relay 521 is opened at contact blades 39 and 41, but relay 521 remains operated during the series of impulses because of its slow-releasing, as by having the indicated copper sleeve surrounding its core, between the core and the winding, as is common practice in the art. As a result, relay 521 remains operated continuously throughout the transmission of a series of impulses.

On each momentary restoration of line relay R1, with hold relay 521 remaining operated, an impulse of current is transmitted to stepping magnet 523 over wire 522, through contact members 39 and 37, and the front contact of member 528. Stepping magnet 523 responds by advancing wiper 527 one step for each impulse received, engaging a separate one of its contacts 1 to 10 on each step. Since wiper 527 is grounded, the lamps 1 to 10 in group 650 are momentarily lighted successively during the receipt of impulses. The lamp which corresponds to the contact on which member 527 stands at the end of the series of impulses remains lighted as a display signal of the value of the digit transmitted and registered.

Off-normal contacts 525 become closed on the first step of wiper 527.

When the registration is to be cleared out, hookswitch contacts 510 are again opened and are allowed to remain open. When this occurs, line relay R1 restores and remains restored, hold relay 521 restoring shortly thereafter.

During the interval required for relay 521 to restore following the restoration of relay R1, an additional, and somewhat prolonged, impulse is transmitted over wire 522 to stepping magnet 523. Wiper 527 is thereby advanced to the next contact, extinguishing the lamp previously lit as a display signal, and lighting the next succeeding lamp. If desired, this action can be avoided by adding one or more control relays, as is done in the signalling art.

When hold relay 521 restores, the circuit of stepping magnet 523 is opened, and a circuit is closed for release magnet 526, from ground at contact blade 39, through contact blade 37, back contact 528, and off-normal contacts 525. The resulting operation of release magnet 526 causes brush 527 to be restored to its illustrated normal condition. Off-normal contacts 525 now open the circuit of release magnet 526, leaving the circuit of Fig. 5 in its illustrated normal condition.

Reversed-action embodiment (Figs. 4 and 6)

Referring now to Fig. 6, the use of the reversed-action relay R2 of Fig. 4 in a typical circuit arrangement will be described.

Fig. 6 is like Fig. 5 except that relay R2 is substituted for relay R1, and the associated control circuit is revised accordingly. Relay R2, because of its described reversed action, does not require a normally closed contact member such as 37 of Fig. 5. Instead, it uses two pairs of normally open contact members 39 and 41, termed 39R, 41R, and 39L, 41L in the respective columns 31 and 32 of Fig. 2.

Upon the closure of a circuit for relay R2, as over the line 512 of Fig. 5, the current builds up in the windings 3 of relay R2, but no movement of the armature (5) thereof occurs for reasons herebefore given, wherefore the contact members of

the relay remain in their illustrated normal open condition.

Upon each momentary interruption of the line, as at impulse contacts 511, the resulting cessation of current flow in the windings 3 of the relay R2 causes the armature (5) to be operated by the delayed action of pole member 4, bringing the contact members 39R and 39L into engagement with their associated fixed contact members 41L and 41R.

Upon each re-establishment of the line circuit as by reclosure of contacts 511, the armature 5 of relay R2 (Figs. 4 and 6) is restored by the action of unshaded pole member 51 in overpowering the shaded pole member 4 upon the rise in line current and consequent rise in the flux through the magnetic structure.

The armature of relay R2 comes to rest in its illustrated restored condition when the line remains closed at the end of the transmission of the series of interruptions impulses, leaving the contact members of Fig. 6 in their illustrated open condition.

Upon each noted momentary closure of the contact members of relay R2, a circuit is momentarily closed by contacts 39R and 41R, over impulse wire 622, through contacts 628, for stepping magnet 623. By the action of magnet 623, wiper 627 is advanced step-by-step over its associated contacts to light a desired lamp 650.

As a further result of each momentary closure of the contacts of relay R2, contacts 39L and 41L close a circuit over wire 624 for release magnet 626. Release magnet 626, as is indicated by the notation "S. O.," is a slow-operating electromagnet, preferably being so arranged by having a winding of considerable inductance and having the usual armature-restoring spring (not shown) adjusted to apply substantial restraining tension. As a consequence, release magnet 626 does not respond to any of the momentary impulses delivered to it along with, and incidental to, the noted delivery of stepping impulses to magnet 623.

When the display lighting of one of the lamps 1 to 10 in group 650 has served its purpose, the opening of the calling line, as at hookswitch contacts 510, causes a cessation of line current. Thereupon relay R2 is operated to close its contact members as previously explained. Since the line current is not resumed at this time, armature 5 soon restores, at the end of a substantial fraction of a second for example.

During the interval when relay R2 is operated following the noted opening of the calling line, release magnet 626 operates because the length of the impulse then delivered thereto over wire 624 exceeds the slow-operate period of the magnet. Upon operating magnet 626 open-circuits stepping magnet 623 at its contacts 628. Magnet 626 remains operated, and wiper 627 is thereby restored to its illustrated normal position. Release magnet 626 soon becomes deenergized, upon the previously noted restoration of relay R2 when the current in shading member 52 of Fig. 4 dies out. The apparatus of Fig. 6 is thus again in its illustrated normal condition.

Performance considerations

The performance of the improved relay under any set of encountered conditions depends upon the design of the relay and the adjustment thereof.

One important design consideration is armature lightness. The armature should be relatively light (having a small effective mass, or

moment of inertia) compared to the available operating force, whereby that force provides a high acceleration according to the general formula that acceleration equals the force divided by the mass ($A=F/M$). Then, the movement of the armature from either of its stop positions to the other can occur readily within the short interval allowable for such movement. In this respect, the armature 5 can very likely be improved by narrowing its width forward of the screws 16 (see Fig. 2), and by correspondingly narrowing the width of pole members 4 and 51, accompanied if necessary by an increase in the thickness of the pole members. Lightness of armature 5 is further promoted by constructing it of a magnetic material having maximum permeability and having a high saturation value, whereby its cross-sectional area can be correspondingly reduced.

In the illustrated embodiment, however, the armature 5 has not been specially shaped for maximum lightness, nor has the use of a magnetic material better than commercially available annealed ingot iron sheet (about one sixteenth inch thickness) been found necessary for the successful use of the relay under the conditions hereinbefore described. Annealed ingot iron is satisfactory for the remaining magnetic items, and soft cold-rolled steel has been used successfully for these items. Whatever the armature shape or material, best results are obtained when the armature itself comprises the most restricted portion (highest reluctance per unit length) of the magnetic circuit, and comprises the portion of the circuit which first reaches saturation when the windings 3 develop sufficient magneto-motive force.

For the most favorable response over a given range of operating conditions, the armature should have a short stroke. That is, the relay should be so adjusted that the normal position and the operated position of armature 5 are as close together as the demands of the contact members (37, 39, 41) reasonably permit. This arises from the fact that the joint control exercised by the pole members 4 and 51 (in operating the armature 5 positively in each of the two directions of movement as the force differential shifts in direction) is best exercised when the armature is never so much closer to one pole member than to the other that the nearer pole unduly restrains the armature from starting its travel toward the distant pole. In all forms of the device which applicant has constructed and tested, the operating range is very limited if the stop positions are such that the armature comes into contact with either pole member, and particularly the unshaded pole member. With the armature contacting a pole member, it is very difficult to adjust the device so that the armature will move to the other pole member unless the pole members are brought much closer together than the drawings indicate. The armature stroke then becomes so small that the resulting movement is less than the requirements of the illustrated type of contact members.

The shading effectiveness of shading member 52 may vary between rather wide limits, such as from 500 to 1000 mhos for the circuit use illustrated in Figures 5 and 6. Considerably higher conductance values of the shading device can be used for interruption impulses of ten per second, so long as the line current and the flux through the shaded pole member have both reached substantially a steady-state condition before the

interruption impulses start. For a higher impulse frequency (such as twenty to thirty impulses per second) of either (1) interruption impulses, or (2) for impulses of current over a circuit which stands open until the first impulse starts, and for low-frequency interruption-impulse situations wherein the initial interruption closely follows the initial line closure, best results are obtained with the illustrated structure when the conductance of shading member 52 does not exceed 500 mhos. Under the noted circumstance, of only a very fleeting impulse, the passage of flux through the shaded pole member is so retarded by a shading device of high conductance that the energy stored in the shaded pole member is insufficient to cause the armature to be urged toward that pole member with sufficient vigor when the current flow is interrupted.

Applicant is aware that certain prior structures, including the disclosures in certain references of record in his prior patent application hereinbefore identified, have employed an armature controlled jointly by an unshaded pole member and an opposed shaded pole member, but no such prior structure, so far as applicant is aware, is capable of attracting its armature in one direction from a first position to a second position responsive to each flow (or sharp rise) of direct current, and of attracting the armature back to its first position responsive to each cessation (or sharp drop) in direct current. In making the foregoing statement, applicant takes the position that any half cycle of alternating current, considered alone, comprises a direct-current impulse that rises to full value and ceases during the period of the half cycle of current.

The several factors governing the ability of a structure of the disclosed character to operate the armature as hereinbefore described include the following:

1. Armature lightness and bias, which govern the ease with which the net magneto-tractive force, available incidental to a rise or a fall in current, can move the armature from its presently occupied position to its other position;

2. Armature sensitivity to flux differential, which is governed by the distance by which the armature in either stop position, is separated from the nearer tractive pole face as compared to its distance of separation from the other tractive pole face;

3. Total flux range, which is limited by the amount of flux which substantially saturates the structure; and

4. Amount of shading or the conductance of shading member, which determines, for any rate of change of total flux, the distribution of such rate of change between the two pole members.

When a device of the disclosed-character has the foregoing factors favorably related according to the description hereinbefore given, it operates in the described useful manner. But, when one or more of the factors is too far out of proportion with the others, the device cannot perform according to the invention. For example, if the shading conductance is too low compared to the flux range and to the armature lightness and sensitivity, the armature cannot change positions responsive to any single impulse of direct current, or half cycle of alternating current, of any strength or sharpness of rise or fall. If the rise or fall be comparatively gradual, then the flux change is gradual, and the flux differential is insufficient to generate a net force differential great enough to withdraw the armature from its

nearer pole member. On the other hand, if the rise or fall of current be abrupt, the flux change is abrupt, but its duration and range are so curtailed by the flux range of the structure, that any resulting net magneto-tractive force is too fleeting to attract the armature away from the nearer pole and move it to its stop position closer to the other pole. On repeated tests, a device so misproportioned responded to 60-cycle alternating current even though it would not respond to any direct-current pulses of any magnitude or rate of change. A partial explanation seems to reside in the fact that the first portion of any half cycle of an established alternating current erases the residual magnetism left in the structure by the preceding half cycle, leaving the structure momentarily demagnetized. It was also noted that the armature, while humming or buzzing because of its relative lightness, stayed at or near the unshaded pole, and did not approach the shaded pole. When a sufficiently large restoring spring tension was applied to cause the armature to approach the shaded pole, it remained there continuously, giving no response to the alternating current. It was further observed that lower frequencies of alternating current had no more effect on the device in question than direct-current pulses all of one polarity.

I claim:

1. In a quick-acting impulse-responsive device, a relatively light armature and means rendering it reciprocable between two positions, an electromagnet for operating the armature, pole means for one pole of the electromagnet divided into two branches ending in pole faces so disposed as to exert opposite tractive forces on the armature in directions toward the two armature positions respectively, shading means for one branch delaying flux change therein with respect to flux change in the other branch incident to the rise and to the fall of current in the winding of the electromagnet responsive to the application and termination of an impulse of direct current to the winding, means included in the said parts and means for rendering the transient resultant of the opposite tractive forces capable of moving the armature from one of its positions to the other responsive to each said rise of current in a series, and rendering it capable of moving the armature back to its said one position responsive to each said fall of current of the series.

2. In a quick-acting impulse-responsive device as set forth in claim 1, means biasing the armature to move to one of its positions when magnetically free to do so, said transient resultant force when in one direction acting with the bias-

ing means to move the armature to its last said position, the said transient resultant force when in the other direction acting against the biasing means to move the armature to its opposite position.

3. In a signal system, impulse-responding means for responding individually to the impulses of series of direct current impulses received over a pulse-transmission line, said impulse-responding means comprising an electromagnet having a winding connected in series with said line, an armature operatively associated with the electromagnet, means defining a first position and a second position for the armature, the electromagnet having a main pole member having a pole face so related to the armature as to attract the armature to its second position responsive to each of said impulses of a series, and means for restoring said armature from its second position to its first position responsive to the cessation of each of the impulses, said restoring means including an auxiliary pole member comprising a branch of the main pole member and having a pole face so related to the armature as to attract it in opposition to the main pole member, and a conducting shading member surrounding the auxiliary pole member and delaying flux change therein with respect to flux change in the main pole member, and means included in the foregoing whereby the effect of the restoring means is prevented from reaching full value on the receipt of an impulse until after the armature has moved from its first position toward its second position, and means included in the foregoing whereby the effect of the restoring means is continued beyond the end of the received impulse to restore the armature from its second position to its first position.

4. In a signal system according to claim 3, means for applying a biasing force to move the armature to one of its positions when it is magnetically free, the impulse-controlled movement of the armature to its said one position being aided by said biasing force, and the impulse-controlled movement of the armature to its other position occurring against said biasing force.
